Primary Examiner — George D. Kirschbaum*Assistant Examiner* — Maria J Edwards(74) *Attorney, Agent, or Firm* — Jason P Mueller; Adams and Reese, LLP**CLAIM**

The ornamental design for an industrial impact safety glove, as shown and described.

DESCRIPTION

FIG. 1 is a front perspective view of an industrial impact safety glove in accordance with the present design;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown are included for the purpose of illustrating a portion of the safety glove that forms no part of the claimed design.

The stippling in the drawings is for shading purposes only. Although shown in the context of a right hand glove, an embodiment of the present invention also may be incorporated in a left hand glove.
